(57) **CLAIM**

The ornamental design for a straw holder, as shown and
described.

DESCRIPTION

FIG. 1 is a top perspective view of a straw holder showing
our new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

The broken lines shown in the drawings are included for the
purpose of illustrating environmental structure and form no
part of the claimed design.

1 Claim, 6 Drawing Sheets
